CLAIM

The ornamental design for a golf club head, as shown and described.

DESCRIPTION

FIG. 1 is a front elevation view of a golf club head;
FIG. 2 is a rear elevation view thereof;
FIG. 3 is a top plan view thereof;
FIG. 4 is a bottom plan view thereof;
FIG. 5 is a heel-side elevation view thereof;
FIG. 6 is a toe-side elevation view thereof; and,
FIG. 7 is a top perspective view thereof.
The broken lines shown in the drawings form no part of the claimed design.
